UNITED STATES PATENT OFFICE

2,434,630

HANDLE FOR CARDBOARD AND FIBRE
BOXES AND THE LIKERobert Van Rosen, New York, N. Y., assignor to
Techniques, Inc., a corporation of New York

Application September 23, 1946, Serial No. 698,853

9 Claims. (Cl. 16—111)

1

The invention relates to handles to be applied to boxes of various kinds and sizes. It may be particularly adapted for use with paper or cardboard or fibre boxes which are provided with slots or apertures through which part of the handle may project to engage the box. If desired, the slots may be in two overlapping parts so as to register when the box is closed, whereby the handle in the slots may also act as a locking device, holding the box closed.

The handle may be cut or formed from a single piece of material, which may be scored or otherwise marked to aid in folding to put the handle in final form for use. It may consist of a top bar or member to lie in the hand when in use, associated with which are side members having projecting legs carrying tongues extending through the slots in the box and held therein by wings on the tongues. In order to give greater strength to the handle and prevent it from collapsing, folding portions may be provided adjacent the top bar adapted to keep parts of the handle apart sufficiently to provide a gripping member of a suitable size to rest conveniently in the hand.

The material of which the device is made may vary and its size and shape may also vary, as may its proportions and relative strength or bulk, compared to the box with which it is to be used. Without limiting the invention, but in order to explain it more fully, there is presented one embodiment of it in the accompanying drawings in which Figure 1 is a plan view of a formed blank from which the handle may be made. Fig. 2 is a perspective view of the blank partially folded. Fig. 3 is a perspective view of the handle fully formed and ready to be inserted in the slots of the box. Fig. 4 is a perspective view of one form of box to which the handle may be applied. Fig. 5 is a perspective view of a box showing the handle applied to it; and Fig. 6 is a transverse vertical section of Fig. 5 on the line 6—6.

The blank consists of a central member or bar 10 acting as a connecting member for the two side members or bars 11 and 12, which are articulated to the member 10. The fold lines on which the various parts are articulated are indicated in dot and dash. Projecting from the ends of the bar 11 are legs 13 and 14 and projecting from the bar 12 are legs 15 and 16. Articulated to the bar 11 and on the side opposite the member 10 and between the legs 13, 14 is a member 17 which, when folded on line 20 as shown in Fig. 6, acts as a spacing member holding apart the bars 11 and 12 when they are folded on lines 21, 22. The

2

member 17 is narrower than the member 10 so that as folded, the legs 14 and 16 and the legs 13 and 15 incline and approach each other at their extremities as shown in Figs. 3, 5 and 6.

5 Articulated to the member 17 at the fold line 23 is a reinforcing member 24 which, as shown in Fig. 6, lies against the bar 12 and is held in place by a tab 25 on 24 which engages in the slot 26 in the top member 10.

10 The handle may be prepared for use by folding first 24 and 17 as shown in Fig. 2. Member 11 may then be folded to bring the tab 25 into the slot 26 and the bar 12 may be folded against 15 24, which will act as a reinforcement of the portion of the handle to be gripped. This folding will bring the ends of legs 13, 15 and 14, 16, respectively, into more or less close proximity or contact, as indicated in Fig. 3. At the ends of each of the legs 13, 14, 15 and 16 are tongues 27, 28, 29 and 30, respectively. Each tongue 27 to 20 30 carries articulated to it a wing 31, 32, 33 and 34, respectively. It will be noted that all wings may be folded outwardly as shown in Fig. 3.

A box of any desirable form may be used with 25 the handle and may be provided with slots through one or more thicknesses of the box material. The slots may be suitably placed and spaced to receive the handle legs. In Fig. 4 is shown a box made up of two members 35 and 36 telescoping at one side so that when closed one side underlies the other. The section 35 is provided with slots 37, 38 adapted to register with slots 39, 40 in section 36. The formed handle may be applied to the box by inserting the tongues 35 27, 29 through registering slots 37, 39 and the tongues 28, 30 through slots 38, 40. As the tongues pass through the slots, the folded wings 31, 32, 33, 34 tend to expand within the box by the natural or inherent elasticity of the material, 40 as shown in Fig. 6, and allow the box to be lifted by the handle which is prevented from being withdrawn through the slots by the wings.

Slots 41, 42, 43 and 44, respectively, on the legs 13, 14, 15 and 16 are provided adjacent the 45 tongues at their ends and act as stops for insertion of the legs and position the box wall between the stops and the wings.

There is thus provided a firmly and definitely 50 fixed sturdy handle for use with boxes of various types.

I claim as my invention:

1. In a handle for a box having slots, two bars, legs extending from the ends of the bars, an intermediate member provided with a slot articulated to and connecting the bars, a spacing mem-

ber articulated to one bar between its legs and extending to the other bar, a reinforcing member articulated to the spacing member and lying in contact with the last mentioned bar, a tab on the reinforcing member engaging the slot in the intermediate member, tongues at the ends of the legs extending through the box slots, wings articulated to the tongues and within the box, and stops on the legs positioning the box between the stops and the wings.

2. In a handle for a box having slots, two bars, legs extending from the ends of the bars, an intermediate member articulated to and connecting the bars, a spacing member articulated to one bar between its legs and extending to the other bar, a reinforcing member articulated to the spacing member and lying in contact with the last mentioned bar, tongues at the ends of the legs extending through the box slots, wings articulated to the tongues and within the box, and stops on the legs positioning the box between the stops and the wings.

3. In a handle for a box having slots, two bars, legs extending from the ends of the bars, an intermediate member articulated to and connecting the bars, a spacing member articulated to one bar between its legs and extending to the other bar, tongues at the ends of the legs extending through the box slots, wings articulated to the tongues and within the box, and stops on the legs positioning the box between the stops and the wings.

4. In a handle for a box having slots, two bars, legs extending from the ends of the bars, an intermediate member provided with a slot articulated to and connecting the bars, a spacing member articulated to one bar between its legs and extending to the other bar, a reinforcing member articulated to the spacing member and lying in contact with the last mentioned bar, a tab on the reinforcing member engaging the slot in the intermediate member, tongues at the ends of the legs extending through the box slots, and wings articulated to the tongues and within the box.

5. In a handle for a box having slots, two bars, legs extending from the ends of the bars, an intermediate member articulated to and connecting the bars, a spacing member articulated to one bar between its legs and extending to the other bar, a reinforcing member articulated to the spacing member and lying in contact with the last mentioned bar, tongues at the ends of the legs extending through the box slots, and wings articulated to the tongues and within the box.

6. In a handle for a box having slots, two bars, legs extending from the ends of the bars, an intermediate member articulated to and connect-

ing the bars, a spacing member articulated to one bar between its legs and extending to the other bar, tongues at the ends of the legs extending through the box slots, and wings articulated to the tongues and within the box.

5. In a handle for a box having slots, two bars, legs extending from the ends of the bars, an intermediate member articulated to and connecting the bars, tongues at the ends of the legs extending through the box slots, wings articulated to the tongues and within the box, and stops on the legs positioning the box between the stops and the wings.

10. In a handle for a box having slots, two bars, legs extending from the ends of the bars, an intermediate member articulated to and connecting the bars, tongues at the ends of the legs extending through the box slots, and wings articulated to the tongues and within the box.

15. In a handle for a box having slots, two bars, legs extending from the ends of the bars, an intermediate member articulated to and connecting the bars, tongues at the ends of the legs extending through the box slots, and wings articulated to the tongues and within the box.

20. In a handle for a box provided with spaced slots, a first bar having a slot in it, a second bar articulated at one edge of the first mentioned bar, legs at the ends of the second bar projecting away from the articulated edge, a third bar articulated to the second bar between the legs and of less width than the first bar and lying substantially parallel to the first bar, a fourth bar, a tab on the fourth bar engaging the slot in the first bar, a fifth bar articulated to the edge of the first

25. bar opposite the second bar and lying in contact with the fourth bar, legs at the ends of the fifth bar projecting away from the articulated edge and having their ends substantially in contact with the ends of the legs of the second bar, all 30. of the legs having slots engaging the box adjacent the box slots, tongues at the ends of all the legs extending through the box slots, and wings articulated to all the leg tongues arranged and constructed to lie against the tongues while

35. 40. passing through the box slots and to expand and engage the inner face of the box.
